Primary Examiner — Bao-Yen T Nguyen*Assistant Examiner* — Jerry Shiuan-Hua Hsu(74) *Attorney, Agent, or Firm* — Wood Herron & Evans LLP(57) **CLAIM**

The ornamental design for a vehicle waistline and fender ingot, as shown and described.

DESCRIPTION

FIG. 1 is a front right perspective view of a vehicle waistline and fender ingot according to the present invention.

FIG. 2 is a front view of the vehicle waistline and fender ingot shown in FIG. 1.

FIG. 3 is a left side view thereof.

FIG. 4 is a right side view thereof; and,

FIG. 5 is a top view thereof.

The broken lines illustrate environmental structure that forms no part of the claimed design.
